US0D1039362S

(12) **United States Design Patent** (10) Patent No.: **US D1,039,362 S**
(45) Date of Patent: ** Aug. 20, 2024

(54) **FASTENING DEVICE**

(71) Applicant: **Zephyros, Inc.**, Romeo, MI (US)

(72) Inventors: **Kyle Deachin**, Romeo, MI (US); **Gary Colston**, Romeo, MI (US)

(73) Assignee: **Zephyros, Inc.**, Romeo, MI (US)

(**) Term: **15 Years**

(21) Appl. No.: **29/830,897**

(22) Filed: **Mar. 16, 2022**

(51) LOC (14) Cl. **08-08**

(52) U.S. Cl.

USPC **D8/349**

(58) **Field of Classification Search**

(57) **CLAIM**

The ornamental design for a fastening device, as shown and described.

DESCRIPTION

FIG. 1 is a perspective view of the present invention.

FIG. 2 is a perspective view thereof;

FIG. 3 is a front elevational view thereof;

FIG. 4 is a side profile view thereof;

FIG. 5 is a side profile view thereof;

FIG. 6 is a rear elevational view thereof;

FIG. 7 is a top-down view thereof; and,

FIG. 8 is a bottom-up view thereof.

1 Claim, 3 Drawing Sheets
